[57] CLAIM

The ornamental design for a self service terminal, as shown and described.

DESCRIPTION

FIG. 1 is a front view of a self service terminal showing my new design;

FIG. 2 is a right side view;

FIG. 3 is a top view;

FIG. 4 is a bottom view; and,

FIG. 5 is a right front perspective view.

The broken line showing of the environment in all views is for illustrative purposes only and forms no part of the claimed design.
